UNITED STATES PATENT OFFICE.

GUSTAVE L. HERZ, OF VIENNA, AUSTRIA-HUNGARY.

ELECTRIC-CABLE TERMINAL.

1,167,820.

Specification of Letters Patent. Patented Jan. 11, 1916.

Application filed April 9, 1913. Serial No. 759,974.

To all whom it may concern:

Be it known that I, GUSTAVE L. HERZ, a subject of the Emperor of Austria-Hungary, and resident of Vienna, Austria-Hungary, 5 have invented a new and useful Improvement in Electric-Cable Terminals, of which the following is a specification.

The object of this invention is to provide novel features of construction whereby an 10 electric cable terminal may be securely fastened to its cable and may be readily attached to and removed from electric connection with the spark plug electrode.

A practical embodiment of my invention 15 is represented in the accompanying drawings, in which—

Figure 1 represents the terminal in side elevation, the terminal being shown secured to the cable and attached to a spark plug, 20 Fig. 2 is a longitudinal central section through the cable and terminal, the spark plug being shown in side elevation, and Fig. 3 is a section taken in the plane of the 25 line A—A' of Fig. 2, looking in the direction of the arrows.

The spark plug is denoted as a whole by 1, its electrode by 2 and a cap by 3. This cap 3 is screwed onto the outer end of the electrode 2 and is provided with a centrally arranged exteriorly screw threaded lug 4 for attachment to the terminal, as will be hereinafter described.

The terminal comprises a non-conducting casing 5, a socket piece 6, a head 7 and a 35 screw eye 8. The screw eye 8 and the socket piece 6 are made of conducting material. The head 7 is embedded in the casing 5 and held against movement therein. This head has a centrally arranged lug 9 which 40 projects into the bore of the socket piece 6 and the socket piece 6 is rotatably mounted on said head by spreading the end of the lug 9 outwardly over a shoulder 10 formed in the bore of the said socket piece.

The socket piece 6 is provided with a 45 milled head 11 exterior to the casing 5 for the purpose of rotating the socket piece. The bore of the socket piece is screw threaded to fit the screw threaded lug 4 of 50 the cap 3 so that the terminal may be rapidly attached to and removed from the

spark plug by a rotary movement of the socket piece 6 in one or the other direction.

The casing 5 is provided with a recess 12 having its walls screw threaded.

The electric conducting cable comprises the usual core 13 and protective covering 14.

The shank of the socket piece 6 extends through the eye of the screw eye 8 and is in electrical contact therewith at all times. The screw threaded portion of the screw eye 8 extends centrally into the recess 12. The end of the cable is inserted into the recess 12 and it has a screw threaded engagement with both the screw eye 8 and the walls of the recess 12. As the cable is screwed into its position, the screw eye is brought into engagement with the wires which form the core 13 of the cable. The screw eye thus holds the cable in its recess and in electric connection with the socket piece, without interfering with the rotary movement of the socket piece.

It is evident that slight changes might be resorted to in the form, construction and arrangement of the several parts without departing from the spirit and scope of my invention; hence I do not wish to limit myself strictly to the structure herein set forth, but—

What I claim is:—

A cable terminal for spark plugs comprising a non-conducting casing, a head embedded therein, said head being provided with a downwardly extending lug having its lower portion outwardly spreading, a socket piece provided with an inwardly extending shoulder adapted to engage the outwardly spreading portion of said lug, thereby forming a swivel connection between said head and said socket piece, said socket piece being screw threaded for engagement with the spark plug.

In testimony, that I claim the foregoing as my invention, I have signed my name in presence of two witnesses, this second day of April 1913.

GUSTAVE L. HERZ.
